CLAIM

The ornamental design for a souvenir headwear, as shown and described.

DESCRIPTION

FIG. 1 is a front perspective view of a souvenir headwear, showing our new design;

FIG. 2 is a front elevation view thereof;

FIG. 3 is a rear elevation view thereof;

FIG. 4 is a left side elevation view thereof, the right side elevation being a mirror image thereof;

FIG. 5 is a top plan view thereof;

FIG. 6 is a bottom plan view thereof; and,

FIG. 7 is a left side elevation view thereof, shown in a used condition.

The broken lines showing the wearer in FIG. 7 depicts environmental subject matter that forms no part of the claimed design, while the remaining broken lines shown in the drawings depict portions of the souvenir headwear that form no part of the claimed design.

In FIGS. 1-7, the use of stippling indicates a contrasting appearance with the adjacent line-shaded portion of the souvenir headwear.
